PULVERIZER

Ervin G. Bailey, Easton, Pa., and George B. Ebersole, Akron, Ohio, assignors to The Babcock & Wilcox Company, Rockleigh, N. J., a corporation of New Jersey

Application April 1, 1943, Serial No. 481,388

8 Claims. (Cl. 83—45)

The present invention relates to the construction and operation of pulverizers of the type in which materials, such as coal, phosphate rock, and the like, are pulverized between one or more grinding surfaces and a relatively moving rolling grinding element or elements and the pulverized material carried out of the grinding zone in suspension in a gaseous carrier medium. A pulverizer of this general type is shown in Schwartz U. S. Patent No. 2,275,595, in which the pulverizing elements are relatively movable upper and lower grinding rings between which a circular row of grinding balls is horizontally arranged and the pulverized material removed from the grinding zone by an annular stream of carrier air passing upwardly through an annular throat and picking up pulverized material discharged from the outer circumferential edge of the lower grinding ring.

In the operation of such pulverizers on coal in a direct fire installation, for example, the carrier air serves as the primary combustion air and is supplied in a predetermined ratio to the fuel supply. Where such pulverizers are used for a relatively wide range of fuel capacity, the amount of carrier air supplied during low load operation drops substantially and the resulting lower velocity usually approaches the minimum velocity required to lift the pulverized material out of the pulverizing zone. In such pulverizers the flow area of the annular throat is usually proportioned to provide a maximum air velocity at an intermediate portion of the throat sufficient over the designed load range to pick up the normally pulverized material discharged from the outer edge of the lower grinding ring. Normally the space at the outer side of the lower grinding ring and in the upper part of the throat is filled with an air-borne mass of material from the pulverizing zone held in suspension by the ascending air stream. Oversize and/or high density particles however tend to drop through the throat against the rising air stream and collect in the subjacent section of the pulverizer, from which they are subsequently swept into a trap or compartment in the pulverizer base. As the pulverizer load decreases with a consequent decrease in the maximum air velocity in the throat, the dribble of particles from the suspended mass through the throat against the lifting effect of the air stream increases. This condition is desirable for the removal of foreign material in the coal, such as pyrites particles, slate, etc., but objectionable and wasteful when the material so discharged includes a sizable percentage of coal.

The general object of our invention is the provision of a pulverizer of the type described which is characterized by an improved construction and arrangement of the parts forming the throat section of the pulverizer. A further and more specific object is the provision of an improved pulverizer throat which provides a substantially uniform air velocity therein throughout its height and circumference and a swirling effect on the air stream beyond the throat, while minimizing obstruction or plugging of the throat by descending material.

The various features of novelty which characterize our invention are pointed out with particularity in the claims annexed to and forming a part of this specification. For a better understanding of the invention, its operating advantages and specific objects attained by its use, reference should be had to the accompanying drawings and descriptive matter in which we have illustrated and described a preferred embodiment of our invention.

Of the drawings:

Fig. 1 is a sectional elevation of a pulverizer constructed in accordance with our invention;

Fig. 2 is a plan view of the throat construction shown in Fig. 1 with parts omitted for clarity;

Fig. 3 is an enlarged view of a portion of the throat shown in Fig. 1;

Fig. 4 is a fragmentary elevation taken on the line 4—4 of Fig. 3; and

Fig. 5 is a plan view of the parts shown in Fig. 4.

The pulverizer illustrated has a substantially cylindrical sectional housing 10 having a base section 11 mounted on a foundation 12. The base section contains the pulverizer drive assembly, including a horizontal pinion shaft 13 arranged to drive a vertical drive shaft 14 axially arranged in the housing. The drive shaft 14 extends upwardly through bearings arranged in a base plate 15 forming the top of the base section 11. The upper section 16 of the housing is of substantially cylindrical form and detachably secured to the base plate 15. The upper housing section encloses the grinding parts of the pulverizer which comprise a drive yoke 17 of generally conical form keyed on the upper part of the drive shaft 14 and an annular lower grinding ring 19 supported on and dowelled to flattened lower portions of the drive yoke. The upper face of the grinding ring 19 is shaped to form a track for a circular row of rolling grinding elements 20, preferably balls of wear resist-

ant alloy steel. The balls 20 support a non-rotary upper grinding ring 21 having a ball track formed in its lower face. An annular spider 22 mounted on the upper ring is provided with lugs 23 arranged in guides on the inner wall of the housing section 16 for preventing rotation, but permitting vertical movement, of the spider and upper grinding ring. A resilient grinding pressure is exerted downwardly on the grinding parts by a number of coil springs 24 engaging the spider.

The material to be pulverized is supplied through a feed spout 25 to the inner side of the upper grinding ring and ball row and falls on the inclined upper surface of the drive yoke 17, being distributed throughout the grinding area by the rotation of the drive yoke and associated parts. The material flows outwardly over the upper surface of the yoke and lower grinding ring, is pulverized between the relatively moving balls and grinding rings, and discharges over the outer edge of the lower grinding ring 19 at an oblique angle to the periphery thereof depending upon the ring speed.

The pulverizer disclosed is of the air swept type having an annular stream of primary or carrier air passing upwardly at the discharge side of the pulverizer grinding zone and through a rotary classifier 30 to one or more valve controlled outlets 31 in the top of the pulverizer. The carrier air is normally preheated and supplied under pressure by a suitable forced draft fan (not shown) to an annular wind box 32 surrounding the lower part of the housing section 16. The stream of carrier air from the annular wind box passes into the pulverizer housing section 16 through passages 33 in the housing at the outer side of the drive yoke. The air stream then flows upwardly through an annular throat passage 34 formed between the outer side of the lower grinding ring 19 and an annular sectional throat plate 35 mounted for adjustment radially on the inner side of the housing section 16. A portion of the throat ring is formed by a segmental pivoted relief gate 36 which swings out to permit the passage of any large pieces of unpulverizable or foreign material, such as tramp iron, into the lower portion of the housing. At a point subsequent to the relief gate 36 in direction of rotation, the base section of the housing is provided with a compartment 40 for the collection of material dropping through the throat 34 including the gate section 36 into the lower part of the housing. The compartment 40 communicates with the grinding zone through a small opening 41 in the housing base plate 15 below which a slideable gate 42 is mounted and manually operable through a rack and pinion system 43 to open and close the opening 41. The compartment 40 is periodically cleaned through a door 44.

In the operation of the pulverizer construction illustrated, the material to be pulverized is supplied to the inner side of the grinding elements and pulverized during its outward passage therethrough. The pulverized material flows forwardly over the outer edge of the lower grinding ring in the direction of rotation of the ring. The pulverized material is then picked up by the annular air stream flowing upwardly through the air throat, the material-laden air passing upwardly to the classifier 30 which separates the coarse and fine particles, the coarse particles being returned to the inner side of the ball row and the fine particles delivered to the pulverizer outlet or outlets 31. The particles

5 of material not swept up by the air stream due to their excessive size or density fall through the subjacent part of the air throat or through the relief gate section thereof into the air entrance area at the outer side of the drive yoke.

10 In coal pulverizers of the character described previously used in a direct firing system, the amount of primary or carrier air supplied is substantially directly proportional to the amount of coal to be pulverized. The air velocity in the throat 34 will correspondingly vary over a relatively wide range with corresponding changes in pulverizer load. Accordingly, in the 15 lower part of the load range, the air velocity in the throat 34 may be close to the minimum velocity necessary to lift the pulverized material out of the pulverizing zone. This condition is complicated by the presence of a mass of pulverized material at the outer side of the ball row and above the throat which is maintained in a floating condition by the rising air stream. The heavier parts of the mass tend to drop into the throat and either clog a portion of the same 20 or fall through into the lower part of the casing. In the lower part of the pulverizer load range, the amount of material dribbling down through the throat may reach such proportions that a substantial increase in the operating costs will 25 result. For that reason and to avoid outages due to the pulverizer becoming plugged, the dribble should desirably be eliminated or restricted to a low value throughout the entire 30 load range of the pulverizer.

35 In accordance with our invention, the parts defining the throat passage 34 are constructed and relatively arranged to provide air flow conditions therethrough which will restrict dribbling of material through the throat to a minimum throughout the designed load range of the 40 pulverizer. For this purpose the throat plate 35 is formed with an upper surface 35a inclined outwardly at an angle of approximately 45° from a point slightly above the level of the 45 surface of the lower grinding ring. The outer side 19a of the lower grinding ring slopes outwardly at a slight angle to the vertical, while the throat plate has a flat surface 35b at a 50 downwardly diverging angle opposite to the ring surface 19a. This downward divergence of the 55 opposite relatively moving sides of the throat facilitates the elimination of any pieces of material lodging in the upper part of the throat. Once such material is worn by the relatively moving parts enough to pass the upper end of throat, it is free to drop through the remainder of the throat.

The throat is subdivided circumferentially by a series of circumferentially spaced lugs or crickets 50 on the face 35b of the throat plate and extending substantially the full height of the throat. The lugs 50 are uniformly spaced circumferentially and shaped to define sloping air passages 51 therebetween of substantially uniform cross-sectional area throughout the height or effective flow length thereof, whereby the rising air-stream will have a constant velocity throughout the throat at any given load. For this purpose each lug is shaped to compensate for the divergence of the surfaces 19a and 35b as well as to effect a swirling of the rising air stream beyond the throat. By sloping the lugs and thereby the air passages 51 the length of the passage relative to height is advantageously increased and the air streams are given a direc-

tion relative to the discharging pulverized material in which the maximum lifting effect thereon is exerted. Each lug progressively increases in cross-sectional area downwardly, having opposite faces 50^a and 50^b arranged at different angles. The slope of these faces may be varied to some extent, but by way of example, the face 50^a is shown at an angle of 35° and the face 50^b at an angle of 55° to the horizontal. The faces 50^a and 50^b are also arranged at an angle to the throat plate face 35^b , an angle of approximately 30° being indicated. The lug face 50^c opposite the grinding ring surface 19^a follows the approximately 9° slope of that surface and is slightly spaced therefrom for operating clearance.

With this arrangement, the air stream from the annular wind box flows upwardly to the restricted throat 34. On reaching the throat it is subdivided by the lugs or crickets 50 into a multiplicity of parallel streams, each of which is directed upwardly at an oblique angle through the corresponding throat passage 51. This direction of the air streams brings them into a position behind the discharging coal particles from the grinding zone, avoiding the turbulence and loss of energy which tend to occur when an air stream cuts across a stream of discharging coal. The maximum theoretical lifting effect is closely approached and the coal-laden air streams reunite at the top of the throat and pass upwardly to the classifier.

It has been found that the dribble is substantially reduced in amount and changed in character with the described throat construction. With this constant velocity throat very little fine material is present in the dribble and those fines are generally pyrites or slate. The provision of a constant velocity over the full height or flow length of the throat provides the necessary time factor required to subject the descending particles to the maximum lifting effect of the air stream and thus increases its effectiveness at any given velocity. It also provides an improved winnowing effect on the descending particles of material, resulting in better separation of the coal and foreign material.

While in accordance with the provisions of the statutes we have illustrated and described herein in the best form of the invention now known to us, those skilled in the art will understand that changes may be made in the form of the apparatus disclosed without departing from the spirit of the invention covered by our claims, and that certain features of the invention may sometimes be used to advantage without a corresponding use of other features. In general, our invention is equally applicable to any pulverizer in which the pulverized material is discharged from the edge of rotating grinding part into an ascending air stream. In the claims, the word "air" is intended to generically cover any gaseous carrier medium suitable for removing pulverized material in the manner described.

We claim:

1. A pulverizer comprising a closed casing, a grinding member mounted within the casing for rotation about a central vertical axis, a plurality of rolling grinding elements in contact with said rotary grinding member, means for introducing material to be ground between said rotary grinding member and grinding elements, there being an annular air throat of varying width between the outer side of said rotary grinding member and the enclosing wall of said casing, means for introducing air upwardly through said throat

to carry away pulverized material in suspension, and means mounted in said throat and arranged to subdivide said throat into a plurality of circumferentially adjacent passages of substantially constant cross-sectional flow area throughout their height.

2. A pulverizer comprising a closed casing, a grinding member mounted within the casing for rotation about a central vertical axis, a plurality of rolling grinding elements in contact with said rotary grinding member, means for introducing material to be ground between said rotary grinding member and grinding elements, there being an annular air throat of varying width between the outer side of said rotary grinding member and the enclosing wall of said casing, means for introducing air upwardly through said throat to carry away pulverized material in suspension, and means mounted in said throat and arranged to subdivide said throat into a plurality of circumferentially adjacent passages of substantially constant cross-sectional flow area throughout their height and arranged to direct an air flow therethrough swirling in the direction of rotation of the adjacent portion of said rotary grinding member.

3. In a direct-fired fuel burning system, a pulverizer comprising a closed casing, a grinding member mounted within the casing for rotation about a central vertical axis, a plurality of rolling grinding elements in contact with said rotary grinding member, means for introducing coal to be ground between said rotary grinding member and grinding elements, there being a downwardly diverging annular air throat between the outer side of said rotary grinding member and the enclosing wall of said casing, means for introducing combustion air upwardly through said throat to carry away pulverized coal in suspension, means for collecting and withdrawing from the lower portion of said casing material falling through said throat, and means mounted in said throat and arranged to subdivide said throat into a plurality of circumferentially adjacent passages of substantially constant cross-sectional flow area throughout their height.

4. In a direct-fired fuel burning system, a pulverizer comprising a closed casing, a grinding member mounted within the casing for rotation about a central vertical axis, a plurality of rolling grinding elements in contact with said rotary grinding member, means for introducing coal to be ground between said rotary grinding member and grinding elements, there being a downwardly diverging annular air throat between the outer side of said rotary grinding member and the enclosing wall of said casing, means for introducing combustion air upwardly through said throat to carry away pulverized coal in suspension, means for collecting and withdrawing from the lower portion of said casing material falling through said throat, and means mounted in said throat and arranged to subdivide said throat into a plurality of circumferentially adjacent passages of substantially constant cross-sectional flow area throughout their height and arranged to direct an air flow therethrough swirling in the direction of rotation of the adjacent portion of said rotary grinding member.

5. A pulverizer comprising a closed casing, a grinding ring mounted within the casing, a plurality of grinding balls on said grinding ring, means for effecting relative movement between said grinding balls and grinding ring, means for introducing material to be ground between said

grinding ring and grinding elements, an annular throat plate radially spaced from said grinding ring to define an annular air throat therebetween receiving pulverized material discharged from said grinding ring, means for introducing air upwardly through said throat to carry away pulverized material in suspension, means for collecting and withdrawing from the lower portion of said casing material falling through said throat, and means in said throat mounted on said throat plate and arranged to subdivide said throat into a plurality of circumferentially adjacent passages of substantially constant cross-sectional flow area throughout their height.

6. A pulverizer comprising a closed casing, a grinding ring mounted within the casing for rotation about a central vertical axis, a plurality of grinding balls on said grinding ring, means for introducing material to be ground between said rotary grinding ring and grinding elements, an annular throat plate radially spaced from said grinding ring to define an annular air throat therebetween receiving pulverized material discharged from said grinding ring, means for introducing air upwardly through said throat to carry away pulverized material in suspension, means for collecting and withdrawing from the lower portion of said casing material falling through said throat, and means in said throat mounted on said throat plate and arranged to subdivide said throat into a plurality of circumferentially adjacent passages arranged to direct an air flow therethrough swirling in the direction of rotation of the adjacent portion of said grinding ring.

7. A pulverizer comprising a closed casing, a grinding ring mounted within the casing, a plurality of grinding balls on said grinding ring, means for effecting relative movement between said grinding balls and grinding ring, means for introducing material to be ground between said grinding ring and grinding elements, an annular

throat plate radially spaced from said grinding ring to define an annular air throat therebetween having a pair of downwardly diverging opposite sides and receiving pulverized material discharged from said grinding ring, means for introducing air upwardly through said throat to carry away pulverized material in suspension, means for collecting and withdrawing from the lower portion of said casing material falling through said throat, and means in said throat mounted on said throat plate and arranged to subdivide said throat into a plurality of circumferentially adjacent passages of substantially constant cross-sectional flow area throughout their height and arranged to direct an air flow therethrough swirling in the direction of discharge of pulverized material from the adjacent portion of said grinding ring.

8. A pulverizer comprising a closed casing, a grinding ring mounted within the casing for rotation about a central vertical axis, a plurality of grinding balls on said grinding ring, means for introducing material to be ground between said rotary grinding ring and grinding elements, an annular throat plate radially spaced from said grinding ring to define an annular air throat therebetween having a pair of downwardly diverging opposite sides and receiving pulverized material discharged from said grinding ring, means for introducing air upwardly through said throat to carry away pulverized material in suspension, means for collecting and withdrawing from the lower portion of said casing material falling through said throat, and lugs mounted on said throat plate and proportioned and arranged to subdivide said throat into a plurality of circumferentially adjacent passages of substantially constant cross-sectional flow area throughout their height.
